UNITED STATES PATENT OFFICE.

GEORGE C. BLICKENSDERFER AND HERVEY SMITH, OF ERIE, PA.

CONVEYER APPARATUS.

SPECIFICATION forming part of Letters Patent No. 295,338, dated March 18, 1884.

Application filed February 4, 1884. (No model.)

To all whom it may concern:

Be it known that we, GEORGE C. BLICKENSDERFER and HERVEY SMITH, citizens of the United States, residing at Erie, in the county of Erie and State of Pennsylvania, have invented certain new and useful Improvements in Conveyer Apparatus; and we do hereby declare the following to be a full, clear, and exact description of the invention, such as will enable others skilled in the art to which it appertains to make and use the same.

This invention relates to conveyers, such as conveyers of packages, cash, &c., in stores, and for other like or similar purposes.

The invention consists in improvements in the construction of the track, the means of switching the cars off the direct track, the means for dispatching the cars from the stations, and other minor improvements that will fully appear in the following description.

In a preceding application by us part of the devices here shown were mentioned, but not specifically claimed nor fully illustrated.

The accompanying drawings illustrate our invention, as follows:

Figure 1 is a perspective view of one of the stations on the lines. Fig. 2 is a side or elevation view of the matter seen in Fig. 1. Fig. 3 is an end view of the same matter. Fig. 4 is an end view of one of the cars. Fig. 5 is a section view (vertically) of the track, the clip for holding the track on the hanger, and of a fragment of one of the car-wheels. Fig. 6 is a plan view of a corner or curve. Fig. 7 is a side view of the curve, looking from its center. Fig. 8 is a vertical section on the line $y-y$ in Fig. 6, looking in the direction of the arrow there seen.

So far as our present invention relates to the track, it consists of the means employed for holding and gripping the track at the several hanging supports or other supports or connections along the line, and of the means for continuing the track by a proper curve at the angles and corners. Figs. 5, 6, 7, and 8 illustrate in detail these improvements.

The tracks, generally speaking, consist of wires of sufficient strength and size, drawn taut, and set at a proper grade to cause the cars to run by gravity. There are two of these tracks, one leading from the cashier's

desk or central station to the salesmen's stations along the route, and is marked B in the drawings, and the other leading from the salesmen's stations to the cashier, and marked 55 in the drawings A. These tracks at angle-points pass through hooks or eyebolts, as at S in Fig. 6, and may thus be drawn taut by tightening devices at one or both of their extremes. If desired, however, the lines may 60 end at each angle, and be drawn taut by tightening devices placed there. At switches, and often at intermediate points, it may be found desirable to support the lines, so as to prevent any chance of sagging or swaying. This 65 may be done by a hanger coming down from the ceiling, or by a bracket, extending out from the wall or from posts. However the support may approach the line, it must take hold of it from below, and must not embrace it fully, so 70 as to interfere with the tread of the car-wheels, and it should also grip the line so as to prevent it being raised up out of its bearing on the support.

In Fig. 5 our construction of this device is 75 fairly shown. C is the hanger or support. On its end a screw-hole is drilled and tapped. The wire or line gripper is formed of two jaws, c^1 and c^2 , which have their inner or clamping faces grooved, so as to embrace the line for 80 more than half of its circumference—that is, so as to grip it above its center, but not far enough above to interfere with the tread of the wheel f' . The jaw c^1 is made with a lug, c^3 , to serve as a bearing or fulcrum, and the screw c^4 85 serves not only to attach the vise to the hanger C, but also as a gripping-screw. The jaw c^2 may be a part of the hanger C, if desired.

In our previous application we have shown the taut wire passing an angle by angular bends, 90 and a piece of curved track attached to it to form a properly curved line; but we showed the main line deflected down and the curved piece lying in the same plane as the main line, so as to form no jolts or obstructions. In the 95 present case we show another method of attaching the curved track, by which the main line does not have to be deflected, for the surface of the curved track is raised above it just enough to allow the flanges of the car-wheels 100 to pass across the main line. This construction is seen in Figs. 6, 7, and 8. J is the curved

track, which is made of cast or wrought metal and formed to the proper curve. At its ends, on the outside, are grooves to receive the line A, and a side piece or cheek, *j*, is attached by 5 a screw, *j'*, and wholly incloses the wire. The construction and clamping effect are the same here as in the vise *c*² *c*³, just above described, only the line is wholly inclosed. The top of the curve track J is inclined, so that it rises gradually from the top of the wire A, and lifts the 10 car-wheels sufficiently above the line A before the curve is made to allow them to pass clear of said line when the curve is reached. The top of the curved piece J is rounded to correspond with the form of the line A, so that the 15 car-wheels encounter no difficulty in running on it. The slight incline that is necessary to carry the car-wheels high enough above the line to cross it will of course slightly impede the 20 car, but not enough to do any harm or stop it. Whatever advantage there may be in this construction lies in the fact that no bending or deflecting the main wire down is required, and if the wire should stretch and need tightening, 25 and thus change the point of attachment of the curve track to the main track, no straightening and redreflecting of the line is required. The middle part of the curve J may be supported by a hanger, C, or it may have arms 30 extending back and lying upon the track A, back of the curve.

The next feature of our invention relates to the construction and operation of the switches. There are two forms of switches shown in the 35 drawings—one for taking the cars off the track, and the other for putting them on, one a receiving and the other a shipping switch. The receiving-switch receives the cars from line B and stops them at the proper salesman's station, and the shipping-switch is the means by 40 which the salesman starts a car on the track A, which, by its incline, carries the car to the cashier. Figs. 1, 2, and 3 show this part of our invention. Both of these switch-tracks 45 extend from the main or direct track to the elevator. Their points—that is, the end next the main track—lie in a vertical plane with the main track, (at a point directly above or directly below the main track,) and their 50 course then deviates from the track in a curve, the same as the switch or siding tracks of ordinary railroads. In our previous application before named the switch-tracks were thus arranged, and we shall not in this instance 55 claim such an arrangement, broadly, as our invention; but in the said previous application it was stated that the switch-track could be so arranged as to pick the car up by its secondary wheels, but no specific or special 60 claim was made to such an operation or the means for doing so. In this instance we show such a construction and operation, and we also show how the car can be put onto the track by a simple arrangement of the switch-track— 65 a feature not named or shown in the said former application.

After having stated, as above, that the

points of the switches lie in a vertical plane with the main track, and that they may be either above or below, it should be stated that 70 the cars are provided with two sets of wheels—one above the other, as seen in Fig. 4 clearly, and also in Figs. 1, 2, and 3—and that one of these sets is used while running on the main track, and the other while running on the 75 switch-track, all of which was clearly set forth in our previous application.

In the drawings, A' is the shipping-switch, and B' the receiving-switch, A being the track running to the cashier's desk, and B the track 80 running from the cashier to the salesmen's stations. We have shown the shipping-switch imposed above the direct track, and the receiving-switch below the direct track. This order may be reversed without any change of 85 effect, or they may be both arranged above or both below, and in no way affect the result or materially change the construction. We have simply shown one above and the other below for the purpose of illustrating the fact that 90 the switch-track may be either superimposed or subimposed, as desired. As stated in our previous application, the essential feature is that the switch-track must lie in a substantially vertical plane with the direct track. It 95 may deviate a little from an exact vertical plane, but not enough to throw the car off its balance. Any such deviation would be detrimental, but it might exist without inoperativeness.

We will notice the operation, first, of a car passing from the direct track to the switch, and, second, of the car passing from the switch to the direct track. Figs. 1 and 2 clearly show these movements, the arrows showing the direction of the car, (or the wheels, which are sometimes shown without the whole car being shown.) In running on the track B, the car has used the upper set of wheels, *f*². When it reaches the switch the lower wheels, *f'*, come 100 in contact with and into tread upon the switch-track B'; and as this track is so adjusted as to be at a less grade or incline than the main track, the wheels *f'* will very quickly be lifted above the main track, and at this point the switch-track curves off and carries the car off 105 to one side. The several stations along a line have their switches adjusted at varying distances from the main track, the most remote being the nearest and the nearest the farthest 110 from the track, and the intermediate in gradative succession; and the sets of wheels on the cars for the several stations are adjusted near to or far from each other, according to the position of the switch-track as to the main track 115 of the station to which the car is dispatched; hence a car destined for the most remote station will have its two sets of wheels so close together that the car will pass all the nearer stations without its secondary wheels coming 120 in contact with the points of the intermediate switches; but when it does reach the last station, the switch there is adjusted near enough 125 to the direct track to receive the secondary 130 wheels.

wheels, as shown in Figs. 1 and 2. The point of the shipping-switch is set at a greater incline than the main track, and as the car runs down the shipping-switch and comes out over the main track it is above it, but quickly runs down the incline, so that the wheels f' will come into tread upon the main line, and the car will then run on those wheels to the central station.

10 It may here be properly stated that the bars or arms F' or F'' , on which the wheels f' or f'' are connected, are pivotally connected to the upright F , so that enough movement may be had to allow the car to hang vertically when the car is going down an incline, but no more movement should be allowed.

D D are guides placed at the points of the receiving-switches, to check any swaying of the car and cause it to surely meet the switch. 20 A roller, d , is fixed on the upright F , to prevent undue friction on the guides. When the car reaches the elevator on the switch, it runs onto a section of track, B' , which is attached to the elevator-frame H by the hangers $h\ h$, and the tilting-bar H' , and by the elevator it can be lowered down to the counter. In shipping the cars from the station, they are set onto the track B' , as seen in Fig. 2, and when the elevator is drawn up so that the track B' 30 will come opposite the shipping-switch A' , the point of the tilting-lever H' comes in contact with the finger I and tilts the bar H' until it hits the stop i . This action gives the car a start and sends it off onto the track A' , whence 35 it runs onto the track A , as above described.

What we claim as new is—

1. In a conveyer apparatus, substantially as shown, the combination, with a track formed of a taut wire, of a hanger or support having thereon a clamp which grips the track below its face and holds it against vertical, lateral, and longitudinal movements, substantially as shown.

2. In a conveyer apparatus, substantially as shown, the combination, with the track, of a hanger or support having thereon the clamp formed of the parts c' , c'' , and c''' , constructed and arranged to operate substantially as and for the purposes set forth.

3. In a conveyer apparatus, substantially as shown, the combination, with a taut wire track which passes corners or curves by angular bends, of a curved track formed of a separate piece of metal, which is clamped upon said main track, substantially as shown, and has its face in a plane above the plane of the main track.

4. In a conveyer apparatus, substantially as shown, the combination, with a taut wire track which passes curves or corners by angular bends, of the curved track-iron J , cheek-pieces $j\ j$, and means, substantially as shown, for clamping said parts upon said main track.

5. In a conveyer apparatus, substantially as shown, the combination, with the main track and a car having two sets of wheels—one above the other—of a switch-track having its point

lying in a vertical plane with the main track, and graded at an angle to the grade of the main track, and adjusted at a distance from the main track corresponding with the distance the said sets of wheels are apart on the car, whereby the car passing said point on one set of wheels on one of said tracks will be engaged by the other track on the other set of wheels, substantially as set forth.

6. In a conveyer apparatus, substantially as shown, the combination, with a main track and a car having two sets of wheels—one above the other—of a switch-track for taking cars off the main track, which has its point lying in a vertical plane with the main track at a distance therefrom corresponding to the distance apart of the sets of wheels on the car, and adjusted so as to receive the tread of the set of wheels not in use on the main track, and which is graded at such an angle to the grade of the main track as to raise the set of wheels used on the main track sufficiently above the same to clear it as the car runs onto the curve of the switch-track, substantially as shown and described.

7. In a conveyer apparatus, substantially as shown, the combination, with a main track and a car having two sets of wheels—one above the other—of a shipping-switch for shipping cars onto said main track, which has its point lying in a vertical plane with the main track, and is at a sufficient distance therefrom at a point near the curve of said switch to carry the set of wheels not in use thereon over the main track, and from thence toward its extreme point grades sufficiently toward the main track to bring the said wheels into tread upon said main track, substantially as shown and described.

8. In a conveyer apparatus, substantially as shown, the combination of the following elements: two main tracks, one grading from and the other to the stations; two switch-tracks at each station, one, A' , for shipping cars onto the track A , which grades from the station, has its point in a vertical plane with the track A , and graded more precipitously than said track A , and the other, B' , for receiving cars from the main track B , which grades toward the station, has its point in a vertical plane with said track B , and graded less precipitously than said track B ; and, finally, a car to be received at and shipped from said station, which has two sets of wheels, one above the other and distanced from each other to correspond with the distance the said switches are adjusted in a vertical line from the said main tracks, substantially as shown and described.

9. In a conveyer apparatus, substantially as shown, the combination of the following elements: two main tracks, A and B , which grade in opposite directions, and arranged one above the other; two switches at each station, one, A' , for placing cars on the track A to ship them from the station, and the other, B' , to take cars off the track B , said switches being arranged one above the other; and, finally, an elevator having a section of track, B'' , which

- can be brought into line with either of said switch-tracks A' or B' by the movement of said elevator, substantially as shown and described.
- 5 10. In a conveyer apparatus, substantially as shown, the combination, with the shipping-switch A', of the elevator H, tilting-bar H, track-section B², finger I, and stop i, as shown, and adapted to be operated substantially as and to the purposes set forth.
11. In a conveyer apparatus, substantially

as shown, the combination, with the shipping-switch A', of the elevator H, tilting-bar H, track-section B², finger I, and stop i, as shown, and for the purposes mentioned.

In testimony whereof we affix our signatures in presence of two witnesses.
